UNITED STATES PATENT OFFICE.

RALPH T. OSMAN, OF ASHLAND, WISCONSIN. ASSIGNOR OF ONE-HALF TO ELLIOTT W. SPARLING, OF ASHLAND, WISCONSIN.

INTERNAL-COMBUSTION ENGINE.

1,390,811.

Specification of Letters Patent. Patented Sept. 13, 1921.

Application filed November 9, 1920. Serial No. 422,859.

To all whom it may concern:

Be it known that I, RALPH T. OSMAN, a citizen of the United States, and resident of Ashland, in the county of Ashland and 5 State of Wisconsin, have invented certain new and useful Improvements in Internal-Combustion Engines; and I do hereby declare that the following is a full, clear, and exact description thereof.

10 My invention relates to engines of the internal combustion type, and more especially to one wherein the head is stationary and the cylinder rotates on its longitudinal axis while the piston reciprocates.

15 An engine of the type described is illustrated in my copending application, Serial No. 366,377, filed March 16, 1920, and the present invention is an improvement on the device illustrated in said application.

20 An important object of my invention is to form and maintain a tight fitting connection between the cylinder and its head, particularly around the inlet and outlet ports in order to prevent any possible leakage of 25 gases around the same.

Another object is to hold the cylinder 30 yieldingly on its seat and to automatically relieve the strain on the engine when through overheating or improper lubrication, there may be a tendency to bind or stick.

35 My invention also comprises novel details of improvement and combinations of parts as will be more fully hereinafter set forth and then pointed out in the claims.

In describing the structure of my invention, reference will be had to the accompanying drawing, in which the single figure is a section through one of the cylinders, parts 40 being shown in elevation in order to better illustrate the structure thereof.

In my former application referred to, I have shown the revolving cylinder as having a straight bearing in the stationary head, 45 and it has been found that due to wearing of the parts, there is a slight tendency toward a leakage or loss of compression. In order to overcome this disadvantage, the present invention has been designed in which 50 the stationary head 1 is provided with a tapered bearing surface 17 in which is mounted the tapered or frusto conical end of the rotating cylinder 16, the lower end of which has a bearing in the housing 15 that 55 is carried and supported by the connecting

ribs 10. Loosely mounted on the lower end of the rotating cylinder and supported by the housing 15 is a driven gear 18, provided with a depending flange 19, in which are formed the inclined slots 20, adapted to receive the pins 21, carried by the cylinder and projecting into the slots. Disposed between the pins 21 and the lower ends of the slots are springs 22 that normally urge the pins upwardly upon the inclined surfaces of the slots 20, thereby causing the tapered end of the cylinder to be held upon its seat or bearing in the head 1. Surrounding the cylinder 16 above the gear 18 is a wear washer 23, held in place by the retaining member 24, 60 that is secured in any suitable manner to the housing 15. Thus it will be seen that the gear 18 is rotatably held in the housing, whereby should a bind or sticking occur between the cylinder and its bearing, the tension of the springs 22 will be overcome, allowing the pins to travel downwardly in the slots 20, which will tend to withdraw the cylinder from its seat or bearing, until the bind is relieved, when the springs will again 65 force it upon its seat.

The lower ends of the connecting ribs 10 are provided with bearings 11 and 12, in which is journaled a crank shaft 13, having the usual crank 14, on which is mounted the 70 connecting rod of the reciprocating piston 28 which is of the usual type except that the end thereof is tapered as at 28' so as to conform to the taper of the cylinder, thereby 75 reducing the space of the compression chamber to the desired size. For driving the gear 18 in timed relation to the crank shaft, a driving pinion 25 is mounted within the housing upon the shaft 26, which in turn is driven by the crank shaft through the bevel gears 27.

The tapered end of the cylinder that forms the compression chamber is provided with ports 29, which as the cylinder rotates, register in turn with the inlet and outlet ports 80 leading to the carburetor and exhaust.

From the foregoing, it will be seen that a very simple and efficient method has been devised for effecting a tight fitting bearing connection between the cylinder and its 85 head, while at the same time the danger of excessive strain or stress upon the motor, due to a possible bind between the cylinder and its bearings, is eliminated.

While I have shown and described a spe- 90

cific method of carrying out my invention, it is well understood that various changes in structural details might be made within the scope of the appended claims.

5 I claim:

1. In an engine of the character described, a head provided with a tapered bearing, a cylinder journaled in said bearing, means for rotating one of said members and a yieldable connection between said means and said rotated member, said connection including a cam for urging the cylinder into said tapered bearing.
- 15 2. An internal combustion engine comprising a stationary head, a rotatable cylinder, bearings in which said cylinder is mounted, one of said bearings being tapered, a gear surrounding said cylinder, means for driving said gear, and a connection between 20 said gear and the cylinder including means adapted to withdraw said cylinder from the tapered bearing upon the occurrence of excessive bind.
- 25 3. An internal combustion engine comprising a rotatable cylinder, bearings in which said cylinder is mounted, one of said bearings being tapered, a ring gear surrounding said cylinder, means for driving said ring gear, and means including yield- 30 able connections between said ring gear and said cylinder for urging said cylinder into close relation with said tapered bearing.
- 35 4. An internal combustion engine comprising a rotatable cylinder, a piston recipro- 35 cable in said cylinder, a crank shaft for driving said piston, bearings in which said cylinder is mounted, one of said bearings being tapered, a ring gear surrounding said cylinder, means for driving said ring gear 40 in timed relation with said crank shaft and means including yieldable connections be- 45 tween said ring gear and said cylinder for urging the cylinder into close relation with said tapered bearing.
- 45 5. An internal combustion engine comprising a rotatable cylinder, bearings in which said cylinder is mounted, one of said bearings being tapered, a ring gear surrounding said cylinder, means for driving 50 said ring gear, yieldable means connected

with said ring gear for rotating said cylinder and means coöperating with said yieldable means for urging the cylinder into close relation with said tapered bearing.

6. An internal combustion engine comprising a rotatable cylinder, a piston recipro- 55 cable in said cylinder, a crank-shaft for driving said piston, bearings in which said cylinder is mounted, one of said bearings being tapered, a ring gear surrounding said cylinder, means for driving said ring gear in timed relation with said crank shaft, 60 yieldable means connected with said ring gear for rotating said cylinder and means coöperating with said yieldable means for 65 urging the cylinder into close relation with said tapered bearing.

7. An internal combustion engine comprising a rotatable cylinder, bearings in which said cylinder is mounted, one of said 70 bearings being tapered, a ring gear surrounding said cylinder, means for driving said ring gear, inclined slots in said ring gear, pins mounted on said cylinder and projecting into said slots, springs in said slots 75 bearing against said pins whereby said cylinder is roated with said ring gear and simultaneously urged in the direction of the tapered bearing.

8. An internal combustion engine comprising a rotatable cylinder, a piston recipro- 80 cable in said cylinder, a crank shaft for driving said piston, in which said cylinder is mounted, one of said bearings being tapered, a ring gear surrounding said cylinder, means for driving said ring gear in times relation with said crank shaft, inclined slots in said ring gear, pins mounted on said cylinder and projecting into said slots, and springs in said slots bearing 85 against said pins whereby said cylinder is rotated with said ring gear and simultaneously urged in the direction of the tapered bearing.

In testimony that I claim the foregoing I 95 have hereunto set my hand at Ashland, in the county of Ashland and State of Wisconsin.

RALPH T. OSMAN.
